RAILWAY TRAFFIC CONTROLLING
SYSTEMRobert M. Phinney, Rochester, N. Y., assignor to
General Railway Signal Company, Rochester,
N. Y.

Application January 15, 1931, Serial No. 508,922

16 Claims. (Cl. 246—3)

This invention relates to railway traffic controlling systems, and more particularly to a system of the unit line wire type, as distinguished from a system of the selector type.

5 In accordance with the present invention, it is proposed to control a switch machine at a distant track switch in accordance with the polarity of current applied to one line circuit and to set up a direction of traffic over said track switch in accordance with the polarity applied to another line circuit, and to indicate over these two circuits the operation of the switch machine, the condition of detector track circuit occupancy and whether or not all of the signals associated with 10 said track switch are at stop. In order to accomplish these results, it is proposed to clear a signal over a line circuit and to open such line circuit as soon as such signal is clear, this signal being held clear through suitable stick arrangement. It thus becomes obvious that if the signal is once cleared it cannot be put to stop manually over this same line circuit, and in accordance with the present invention it is proposed to put such signal to stop manually over 15 said another line circuit used for controlling the operation of the track switch.

Other objects, purposes and characteristic features of the invention will be in part obvious from the accompanying drawing and will in part be more specifically pointed out hereinafter.

In describing the invention in detail, reference will be made to the single drawing, showing conventionally the trackway apparatus at one end of a distant passing siding, together with the central office equipment for controlling and receiving indications from said trackway apparatus.

Referring to the drawing the track rails 1 have been shown divided into blocks by insulating joints 2 to provide the usual track circuits, of 20 which the detector track circuit containing the detector track relay DT and the battery 4 have been shown.

Although the invention may be applied to double track railroads, that is where traffic moves only in one direction, it has been shown applied to a single track railway system preferably signalled by a signalling system of the absolute-permissive-block type, of which a portion of a single track section O and a portion of a passing siding 50 PS only have been illustrated. This passing siding PS includes a track switch SW operable through the medium of the switch machine SM, and this track switch SW has associated therewith starting signals 7 and 7^d for governing the entrance from the main track and the side track

of the passing siding, respectively, into the single track section O, and has also associated therewith an entering signal 8 and a take-siding signal 8^d.

The switch machine SM is controlled by a polar neutral relay WZ through suitable circuits conventionally shown by the dotted line 9. This switch machine is provided with contacts therein for controlling a polar switch machine repeater relay WP, which relay is energized only if the switch machine assumes its full normal or full reverse locked position, and is energized by current of positive polarity when the switch machine assumes its normal position and current of negative polarity when the switch machine assumes its reverse position. The signals 7, 7^d, 8 and 8^d are controlled through the medium of a polar neutral control relay SZ, the direction of traffic being determined by the polar position of this signal control relay SZ, and the main track or side track signal is selected in accordance with the polar position of the switch machine repeater relay WP, providing this relay WP is in correspondence with the switch machine relay WZ. This switch machine repeater relay WP is energized through the following circuit:—beginning at the terminal (+) or the terminal (—), depending upon whether the switch is in its normal or reverse position, contact 10, wire 11 or 12, wire 13, winding of the relay WP to the midpoint C of said battery.

A relay M is provided to indicate whether or not all of the signals 7, 7^d, 8 and 8^d assume the stop position, this relay being energized through the following circuit:—beginning at the terminal (+) of a suitable battery, contact 14 of the signal 8^d, wire 15, contact 16 closed only when the signal 8 is in the stop position, wire 17, contact 18 closed only when the signal 7 is in the stop position, wire 19, contact 20 closed only when the signal 7^d is in the stop position, wire 21, winding of the relay M to the other terminal (—) of said battery.

The wayside apparatus also includes a relay OS which may be energized by current of one or the other polarity depending upon whether the relay WP is energized or deenergized, relay OS being energized through the following circuit:—beginning at the terminal (+) or terminal (—) depending upon the condition of energization of the relay WP, contact 23 of the relay WP, wire 24, front contact 25 of the relay DT, wire 26, winding of the relay OS to the midpoint C of said battery.

In the central office DO, has been illustrated a

55

signal lever SL for controlling the signal relay SZ, and a switch control lever WL for controlling the switch machine relay WZ. Associated with the signal lever SL are two direction indicating lamps WI and EI for indicating through the medium of the indicating relay SOS the direction of traffic set up by signals associated with the switch SW, and similarly, there is an OS indicating lamp OSI associated with the switch control lever WL, which indicates through the medium of the relay OSR the initiation of operation of the switch machine and the completion of its stroke and the occupancy of the detector track circuit associated with the track switch SW. The central office apparatus also includes two lever repeating relays R¹ and R² the function of which is more readily described hereinafter.

Operation

As shown in the drawing, the switch machine lever WL assumes its main track position, under which condition the relay WZ is energized through the following circuit:—beginning at the terminal (+) of the central office split battery, wire 38, contact of the lever WL, wire 31, back contact 32 of the relay R¹, wires 33 and 34, back contact 35 of the relay R², wires 36 and 37, winding of the relay OSR, line wire 38, front contact 39 of the relay OS, wire 40, winding of the relay WZ through a suitable return wire C connected to the midpoint of the office battery.

Let us now assume that there is an east bound train in the single track section O and that the operator wishes this train to proceed into the main track of this passing siding PS. In order to inform the engineer of the train of this fact the operator will, to effect energization of the relay SZ, move his lever SL to the right, thereby closing the following circuit for the relay R²:—beginning at the terminal (+) of the central office battery, contact 42 of the lever SL, wire 43, winding of the relay R² to the other terminal (—) of said battery. The closure of this circuit will effect energization of the relay R² thereby closing the following circuit for the relay SZ:—beginning at the terminal (+) of the central office battery, front contact 45 of the relay R², wire 46, indicating relay SOS, line wire 47, front contact 48 of the relay M, wire 49, front contact 50 of the relay WZ, wire 51, winding of the relay SZ, to the common return wire C connected to the midpoint of the office battery.

The completion of this circuit will energize the relay SZ to the right, thereby closing the clearing circuit for the signal 8 which may be traced as follows:—beginning at the terminal (+) of the way station battery, front contact 53 of the detector track relay DT, wire 54, front contact 55 of the relay SZ, wire 56, polar contact 57 of the relay SZ to the right, wires 58 and 59, polar contact 60 of the relay WZ, wire 61, neutral contact 62 of the relay WZ, wire 63, neutral contact 64 of the relay WP, wire 65, polar contact 66 of the relay WP, wire 67, neutral contact 68 of the home relay 8H (controlled in accordance with traffic conditions in advance), wire 69, polar contact 70 of the relay 8H through the clear or caution wire, conventionally shown by the dotted line 71, depending on traffic conditions in advance, through the mechanism of the signal 8 for operating this signal 8 to its clear position. Although these signals 7, 7^d, 8 and 8^d may be either light signals or semaphore signals they have for convenience been illustrated as semaphore signals.

With the signal 8 assuming its clear or caution

position its contact 16 is opened, thereby effecting deenergization of the relay M and causing the relay SZ to be energized through the following stick circuit:—beginning at the terminal (+) of the way station split battery, polar contact 73 of the relay SZ, wire 74, neutral contact 75 of the relay SZ, wire 76, back contact 48 of the relay M, wire 49, front contact 50 of relay WZ, wire 51, winding of the relay SZ, to the midpoint C of the way station battery. It is thus noted that clearing of the signal 8 effected dropping of the contact 48 and thereby effected opening of the line circuit including the line wire 41. The relay SZ, which is sufficiently slow to release to retain its armature in attracted position during the dropping of 48, was however not deenergized because a properly poled stick circuit for this relay was closed upon dropping of the contact 48. In the central office, however, the relay SOS was deenergized by the clearing of the signal 8, due to the opening of the circuit for SOS at 48 and the dropping of this relay SOS closed the following circuit for the east bound indicator EI:—beginning at the terminal (+) of the central office battery, back contact 77 of the relay SOS, wire 78, front contact 79 of the relay R², wire 80, indicating lamp EI, to the other terminal (—) of the central office battery.

Let us now assume that the east bound train under consideration moving in the single track section O accepts the signal 8, and proceeds into the main track of the passing siding PS. As the train in question treads upon the detector track circuit containing the track relay DT it effects deenergization of this track relay DT, thereby breaking the energizing circuit for the relay OS at the contact 25 and effecting breaking of the circuit for the signal 8 at the contact 53 of this relay DT. The opening of the contact 25 effects deenergization of the relay OS, and dropping of the contact 39 in the energizing circuit for the relay WZ which is slightly slow acting, so the relay WZ is not deenergized because the following stick circuit for this relay WZ is closed:—beginning at the terminal (+) of the way station battery, polar contact 32 of the relay WZ, wire 33, front contact 34 of the relay WZ, wire 35, back contact 39 of the relay OS, wire 40, winding of the relay WZ, to the midpoint C of the way station battery. Dropping of the contact 39 of the relay OS although it does not effect dropping of the relay WZ does effect deenergization of the indicating relay OSR in the central office DO, thereby completing the following energizing circuit for the detector track occupancy indicator OSI:—beginning at the terminal (+) of the central office battery, wire 30, switch machine lever WL, wire 31, back contact 32 of the relay R¹, wires 33 and 36, contact of the lever SL, wires 37 and 38, back contact 39 of the relay OSR, wire 90, indicating lamp OSI, to the midpoint C of the central office battery. The operator is thus informed that the detector track circuit containing the track relay DT is occupied by the passing train.

Also, as heretofore pointed out the passage of the train by the signal 8 moves the signal 8 to its stop position by reason of the opening of the contact 53 of the detector track relay DT. This movement of the signal 8 to the stop position will of course reclose the energizing circuit for the signals-at-stop relay M, thereby effecting re-energization of the indicating relay SOS and opening of its contact 77, whereby the east bound indicating lamp EI is extinguished, informing

the operator that the formerly cleared east bound signal has moved to its stop position. As soon as the rear end of the train passes off of the detector track circuit containing track relay DT, this relay DT is reenergized, thereby effecting reenergization of the relay OS, which in turn effects reenergization of the indicating relay OSR and the extinguishment of the indicating lamp OSI in the central office. The east bound signal lamp EI, will, however, not be reenergized at this time, because the signal 8 is now held at stop by reason of deenergization of the home relay 8H through the medium of the track relay T comprising part of the track circuit for the main track of the passing siding PS, and which is normally energized by the track battery 5. As soon as the train in question passes in an eastwardly direction to an extent to permit energization of the home relay 8H to its negative caution position, the signal 8 will be operated to its caution indicating position, thereby effecting deenergization of the relay M and reenergization of the east bound signal indicating lamp EI.

Let us now assume that there is a west bound train occupying the side track of the passing siding PS and that the dispatcher wishes this train to proceed into the single track section O. To accomplish this it will of course be necessary for the dispatcher to operate the track switch SW to its take-siding position, and this is accomplished by operating the lever WL to its dotted position, through the medium of which the relay WZ is energized to its left hand position through a circuit heretofore traced, except that it is now connected to the (—) terminal of the central office split battery. Operation of the relay WZ to its left hand position will effect operation of the switch machine SM to its take-siding position through the medium of suitable wires conventionally shown by the dotted line 9.

As soon as the switch machine SM is unlocked (this switch machine preferably being one of the general type as shown in Howe Patent No. 1,466,903 dated September 4, 1923) the switch machine repeater relay WP is deenergized. This deenergization of the relay WP will effect dropping of its contact 23 thereby changing the polarity applied to the relay OS, so that the magnetism in the core structure of the relay OS must pass through zero and effect momentary deenergization of the relay OS, and therefore of OSR. This momentary deenergization of the relay OS effects momentary flashing of the indicating lamp OSI in the central office, for reasons heretofore given, thereby informing the dispatcher that the switch machine has begun its operating stroke. As soon as the switch machine has completed its operating stroke the relay WP is again energized but is energized to its left hand dotted position, thereby effecting operation of its polar contacts to their left hand dotted position. Further, this reenergization of the relay WP reverses the polarity of the current applied to the relay OS, thereby causing momentary dropping of the relay OS and another flash of the indicating lamp OSI, signifying the completion of the stroke of the switch machine SM.

Since the operator wishes to set up west bound traffic movement, he will operate his signal lever SL to its left hand position, thereby completing the following energizing circuit for the relay R¹:—beginning at the terminal (+) of the central office battery, contact 92 of the lever SL, wire 93, winding of the relay R¹ to the other terminal (—) of said battery. This movement

of the lever SL will of course effect deenergization of the relay R², so that the signal control relay SZ will now be energized to its left hand dotted position through the following circuit:—beginning at the terminal (—) of the central office split battery, front contact 95 of the relay R¹, wire 96, back contact 45 of the relay R², wire 46, winding of the relay SOS and elements 47, 48, 49, 50 and 51 through the winding of the relay SZ, to a common return wire C connected to the midpoint of the office split battery.

With the relay SZ now operated to its left hand position and with relays WZ and WP assuming their left hand position the dwarf starting signal 7^d is cleared through the following circuit:—beginning at the terminal (+) of the way station battery, front contact 53 of the relay DT, elements 54, 55, 56, 57, 100, 101, 102, 103, 104, 105, 106, 107, 108, 109, 110 and 111, polar contact 112 of the home relay 7H through the clear or caution wire conventionally shown by the dotted line 113 to the dwarf starting signal 7^d. The train under consideration may now proceed in response to the clearing of the starting signal 7^d into the single track section O, and the occupancy of the detector track circuit will again be indicated by the indicating lamp OSI in a manner as already heretofore explained, and also the fact whether the signal 7^d assumes the stop or a proceed position will be indicated through the medium of a west bound traffic light WI, the circuit of which includes the wires 114 and 115 and the front contact 116 of the relay R¹, readily traced in the drawings.

Attention is particularly directed to the polar contacts 60 of the relay WZ and 66 of relay WP and their associated wiring, from which it will readily appear that the signal 8 or 8^d cannot be cleared unless the contacts 60 and 66 assume like polar positions. In other words, these signals 8 and 8^d cannot be cleared unless the position of the switch machine as manifested by the polar position of the relay WP corresponds to the polar position of the relay WZ for controlling this switch machine SM. It is thus apparent that the signals 8 and 8^d cannot be cleared unless the switch machine SM has followed a change in the position of the relay WZ. What has been said in regard to contacts 60 and 66 and signals 8 and 8^d is also true of the polar contact 102 and 108 of the relays WP and WZ, respectively, and the signals 7 and 7^d. The purpose of this check on correspondence of devices is to check the operativeness of the switch machine, switch points and the like, whereby if the switch fails to respond to the change of relay WZ none of the signals can be cleared.

Let us now assume that the apparatus has again been returned to its normal position, as shown in the drawings, and that the dispatcher decides to clear the signal 7 to allow a west bound train to pass from the main track of the passing siding PS into the single track section O, and in order to do so moves his signal lever SL to its left hand position. This movement of the lever SL to the left will of course effect energization of the relay R¹, through the medium of contact 95 of which the relay SZ will be operated to its left hand dotted position, and close the following energizing circuit for the mechanism of signal 7:—beginning at the terminal (+) of the way station battery, front contact 53 of the relay DT, elements 54, 55, 56, 57, 100, 108, 107, 106, 105, 104, 103, 102, 121, 122 and 123, polar contact 75

124 of the relay 7H, the clear or caution wire conventionally shown by the dotted line 125, through the signal mechanism of signal 7, to the other terminal of the way station battery. 5 The clearing of the signal 7, assuming traffic conditions in advance thereof to be favorable, will effect deenergization of the relay M and dropping of its contact 48, which in turn will cause the signal relay SZ to be stuck 10 up through a stick circuit the same as heretofore traced, except that the contact 73 now assumes the left hand dotted position. Clearing of the signal 7 will of course result in illumination of the indicating lamp WI for reasons heretofore given. 15 Let us now assume that the operator has made a mistake and wishes to again put the signal 7 to stop. It is readily apparent that the operator cannot deenergize the signal relay SZ through the medium of the line circuit 47, because the 20 contact 48 of the relay M is in its retracted position and has broken this line circuit. The operator will, however, return his signal lever SL to the middle position thereby effecting deenergization of the relay SZ through the medium of 25 the switch machine line wire 38, as presently explained. Movement of the lever SL to the middle position will break the energizing circuit for the relay WZ by reason of the fact that the contact 32 of the relay R¹ in the central office DO will 30 drop only a short time after the shunt comprising wires 127, lever SL and wire 86, around this contact 32 is broken, so that the relay WZ is momentarily deenergized, that is, during the time required for the relay R¹ to assume its deenergized position. This momentary deenergization 35 of the relay WZ, due in part to the long wipe stationary contact with which control 92 of lever SL cooperates, will momentarily break the stick circuit for the relay SZ at the front contact 50 of the relay WZ. It will be noted, however, that dropping of the contact 50 of the relay WZ will not effect breaking of the line circuit 47 under 40 conditions when the contact 48 of the relay M is assuming its energized position, as may at times be the case, because with the contact 50 in its 45 retracted position current may flow through the resistance unit 128 to the common return wire C connected to the midpoint of the central office battery. The resistance unit is a substitute for 50 the relay SZ and therefore its impedance is preferably the same as that of the relay SZ. Momentary breaking of the stick circuit for the signal control relay SZ will effect deenergization of this relay SZ, and since the lever SL in the central office DO is now in its middle position the relay SZ will remain deenergized. 55

In the same manner, as the delay in the dropping of the relay R¹ has effected momentary deenergization of the switch machine control relay 60 WZ due to movement of the lever SL from its left hand position to its middle position as just explained, the slow dropping of the relay R², in order that the contact 35 of relay R² shall not make its back contact and hence close the circuit 65 for relay WZ, until a short time after the shunt, including wire 87, lever SL, and wire 86, is opened by movement of lever SL to its mid-position will effect momentary deenergization of the switch machine relay WZ due to movement of the signal 70 lever SL from its right hand to its middle position. In other words, the movement of the signal lever SL from either of its two extreme positions to the middle or the other of its two extreme positions will effect momentary breaking of the energizing circuit for the switch machine relay WZ, 75

and this in turn will effect momentary opening of the stick circuit for the signal control relay SZ, so that this signal control relay SZ may be operated to its deenergized position manually through the medium of the control circuit for 5 the switch machine relay WZ, and this feature of applicant's construction permits a signal to be put to stop manually from the central office.

It should be noted that the control circuit for the take-siding signal 8^d includes only one traffic 10 controlled contact, namely contact 130 of the detector track relay DT. This is on the assumption that the side track of the passing siding PS is not track circuited. If the side track is to be track circuited, the signal 8^d is controlled in accordance 15 with traffic conditions in advance in the same manner as the signal 8 has been shown controlled.

Applicant has thus provided an arrangement of 20 circuits and devices whereby a track switch may be controlled from a local office and four signals associated with said track switch may be controlled from the local office through the medium of two direct current polar circuits, and provision has been made whereby the same circuits through 25 the medium of the same current sources may transmit continuing indications to said local office of the occupancy of the detector track circuit associated with such track switch, the indicating 30 conditions of signals associated with such track switch and further the initiation and completion of the stroke of the switch machine.

Having thus shown and described one rather 35 specific embodiment of my present invention, it is desired to be understood that the particular embodiment of the invention illustrated has not been selected for the purpose of showing the scope of the invention or the exact construction 40 preferably employed in practicing the invention, but has been selected for the purpose of facilitating disclosure of the underlying principles of the invention and one arrangement for carrying out these principles, and that various changes, modifications and additions may be made to adapt the 45 invention to the particular problem encountered in practicing the same, all without departing from the spirit or scope of the invention or the idea of means underlying the same, except as demanded by the scope of the following claims. 50

What I claim as new is:—

1. Signal control and indicating means comprising, a distant signal, a relay associated with said signal for controlling said signal, a local office, a line circuit connecting said relay and office, means for energizing said relay to clear said signal, means for opening said line circuit and disconnecting said relay therefrom in response to clearing of said signal to thereby deenergize said line circuit, and means at said office for indicating when said line circuit is deenergized. 55

2. Signal control and indicating means comprising, a distant signal, a stick relay associated with said signal for controlling said signal, a local office, a line circuit connecting said relay and office, means for energizing said relay to clear said signal, a stick circuit for maintaining said stick relay energized irrespective of said line circuit, means for opening said line circuit in response to clearing of said signal, and means at said office for indicating the continuity of said line circuit. 65

3. Signal control and indicating means comprising, a distant signal, a stick relay associated with said signal for controlling said signal, a local office, a line circuit connecting said relay and 70

office, means for energizing said relay to clear said signal, a stick circuit for maintaining said stick relay energized irrespective of said line circuit, means for opening said line circuit in response to clearing of said signal, means at said office for indicating the continuity of said line circuit, and other means for breaking said stick circuit.

4. Signal control and indicating means comprising, a distant signal, a stick relay associated with said signal for controlling said signal, a local office, a line circuit connecting said relay and office, means for energizing said relay to clear said signal, a stick circuit for maintaining said stick relay energized irrespective of said line circuit, means for opening said line circuit in response to clearing of said signal, means at said office for indicating the continuity of said line circuit at said signal and in turn the indicating condition of said signal, and other means for breaking said stick circuit.

5. In combination, a distant track switch, a switch control relay for controlling said track switch, a signal associated with said switch, a signal control relay for controlling said signal, two line circuits one for controlling said switch control relay and the other for controlling said signal control relay connecting a local office with said track switch location, a stick circuit for said signal control relay including a source of current at said signal, an indicating relay included in series with each of said line circuits at said office for manifesting the continuity of said line circuits, means for opening the line circuit for said switch control relay upon passage of a train over said track switch, means for opening the line circuit for said signal control relay upon clearing of said signal said signal control relay being maintained energized through its stick circuit, and means for breaking said stick circuit upon deenergization of said switch control relay.

6. In combination, a distant track switch, a switch control relay for controlling said track switch, a signal associated with said switch, a signal control relay for controlling said signal, two line circuits one for controlling said switch control relay and the other for controlling said signal control relay connecting a local office with said track switch location, a stick circuit for said signal control relay including a source of current at said signal, an indicating relay included in series with each of said line circuits at said office for manifesting the continuity of said line circuits, means for opening the line circuit for said switch control relay upon passage of a train over said track switch, means for opening the line circuit for said signal control relay upon clearing of said signal, said signal control relay being maintained energized through its stick circuit, and a front contact of said switch machine relay included in said stick circuit.

7. In combination, a distant track switch, a switch control relay for controlling said track switch, a signal associated with said switch, a signal control relay for controlling said signal, two line circuits one for controlling said switch control relay and the other for controlling said signal control relay connecting a local office with said track switch location, a stick circuit for said signal control relay including a source of current at said signal, an indicating relay included in series in the line circuit including said signal control relay, means for opening the line circuit containing said signal control relay upon clearing of said signal, said signal control relay being main-

tained energized through its stick circuit, and means for breaking said stick circuit upon deenergization of said switch control relay.

8. In combination, a distant track switch, a switch control relay for controlling said track switch, a signal associated with said switch, a signal control relay for controlling said signal, two line circuits one for controlling said switch control relay and the other for controlling said signal control relay connecting a local office with said track switch location, a stick circuit for said signal control relay including a source of current at said signal, an indicating relay included in series in the line circuit including said signal control relay, means for opening the line circuit containing said signal control relay upon clearing of said signal, said signal control relay being maintained energized through its stick circuit, and a front contact of said switch control relay included in said stick circuit.

9. In combination, a local office, a distant way station, a track switch at said station, a signal associated with said track switch, two line circuits connecting said local office and said way station, means for controlling operation of said track switch over one of said line circuits, means for controlling said signal through the medium of both of said line circuits, means for indicating train occupancy of said track switch over one of said line circuits, and means for indicating the clearing of said signal over said other line circuit.

10. In combination, a local office, a distant way station, a track switch at said way station, a signal associated with said track switch, two line circuits connecting said local office and said way station, means for controlling operation of said track switch over one of said line circuits, means for controlling said signal through the medium of both of said line circuits, means for distinctively indicating train occupancy of said track switch and operation of said track switch over one of said line circuits, and means for indicating the clearing of said signal over said other line circuit.

11. In combination, a distant location, a control office, two separate line circuits connecting the office with the distant location, a stick device at the distant location picked up over one of the line circuits, a local stick circuit for said stick device, a second device at the distant location energized through the other line circuit, means including said other line circuit for breaking the stick circuit of said stick device, and other means controlled over said one line circuit when said stick device is stuck up.

12. In combination, a distant location, a control office, two line circuits connecting the office with the distant location, a stick relay at the distant location picked up over one of the line circuits, a local stick circuit for said stick relay, a second relay at the distant location energized through the other line circuit, the stick circuit of said stick relay including a front point of said second relay, and other means controlled over said one line circuit when said stick relay is stuck up.

13. In combination, a local office, a distant way station, a track switch at said station, a signal associated with said track switch, a switch control relay, a signal control relay, two line circuits connecting said local office and said way station including respectively said switch control relay and said signal control relay, the line circuit including said signal control relay also including a front contact of said switch control relay, whereby the operation of said track switch is controlled from

one extreme position to the other over one only of said line circuits, and the operation of said signal is controlled through the medium of each of said line circuits separately.

- 5 14. In combination, a distant track switch, a switch control relay for controlling said track switch, a signal associated with said track switch, a signal control relay for controlling said signal, two line circuits one for controlling said switch 10 control relay and the other for controlling said signal control relay and both connecting a local office with said track switch location, a control lever at the local office for each of said two line circuits, a stick circuit for said signal control relay including a source of current at said signal, means for energizing said line circuits depending upon the position of said control levers, means for opening the line circuit for said signal control relay and closing its stick circuit upon the 15 clearing of said signal, means for breaking said stick circuit for said signal control relay upon de-energization of said switch control relay, and means other than the lever for said switch control line circuit for momentarily deenergizing said 20 switch control relay.

- 25 15. In combination, a distant track switch, a switch control relay for controlling said track switch, a signal associated with said track switch, a signal control relay for controlling said signal, a signal control lever at a local office, having clearing and stop positions, a switch control lever at a local office, a line circuit connecting said signal control lever and said signal control relay, a line circuit connecting said switch control lever and said switch control relay, a stick circuit for 30 said signal control relay including a source of cur- 35

rent at said signal, means for opening the line circuit for said signal control relay upon clearing of said signal and causing said signal control relay to be maintained energized through its said stick circuit, means for breaking said stick circuit of said signal control relay upon deenergization of said switch control relay, and means for momentarily causing the deenergization of said switch control relay upon the movement of said signal control lever from a clearing position 10 to a stop position.

5 16. In combination, a remote signal for governing railway traffic and capable of being cleared or at stop, a signal control relay for controlling said signal, a line circuit connecting a local office 15 with said signal control relay, a signal control lever for energizing said line circuit when in a clearing position and for deenergizing said line circuit when in a stop position, means for opening said line circuit for said signal control relay upon 20 the clearing of said signal, a stick circuit for said signal control relay closed when said signal is cleared, a neutral relay including in series in said line circuit at the local office, indicator lamps selected in accordance with the position of said signal lever and energized only when said neutral 25 relay is deenergized whereby the actuation of said signal lever to a clearing position fails to energize one of said indicator lamps until said signal has cleared thereby opening said line circuit and 30 deenergizing said neutral relay, and means for breaking said stick circuit of said signal control relay upon the return of said signal lever to a stop position.

ROBERT M. PHINNEY. 35
